Primary Examiner — Wan Laymon(74) *Attorney, Agent, or Firm* — Jacobson Holman PLLC(57) **CLAIM**

The ornamental design for a tray table for dental chair, as shown and described.

DESCRIPTION

FIG. 1 is a perspective view for a tray table for dental chair showing our new design,

FIG. 2 is a front view thereof,

FIG. 3 is a rear view thereof,

FIG. 4 is a left side view thereof,

FIG. 5 is a right side view thereof,

FIG. 6 is a top view thereof; and,

FIG. 7 is a bottom view thereof.

Portions of the tray table for dental chair shown in broken lines form no part of the claimed design.
